DESIGN FOR A JUICE EXTRACTOR

Herbert C. Johnson, Wilmette, Ill., assignor to National Die Casting Company, Chicago, Ill., a corporation of Illinois

Application August 2, 1944, Serial No. 114,690

Term of patent 14 years

(Cl. D89—1)

To all whom it may concern:

Be it known that I, Herbert C. Johnson, a citizen of the United States, residing at Wilmette, county of Cook, State of Illinois, have invented a new, original, and ornamental Design for a Juice Extractor, of which the following is a specification, reference being had to the accompanying drawings, forming a part thereof.

I claim:

The ornamental design for a juice extractor, as shown.

HERBERT C. JOHNSON.
